UNITED STATES PATENT OFFICE.

HARDING ALLEN, OF BARRE, MASSACHUSETTS.

BELT DRIVING MECHANISM.

1,121,599.

Specification of Letters Patent. Patented Dec. 22, 1914.

Application filed November 10, 1910. Serial No. 591,595.

To all whom it may concern:

Be it known that I, HARDING ALLEN, a citizen of the United States, residing at Barre, in the county of Worcester and State of Massachusetts, have invented a new and useful Belt Driving Mechanism, of which the following is a specification.

The object of this invention is to provide a new and improved belt driving mechanism by which power can be transmitted at different speeds from a power shaft to a driven shaft.

The invention, while capable of general use, has been devised particularly for use in connection with machine tools, such as drilling machines, which have a vertical spindle.

The best form of apparatus known to me for practising the invention is shown in the accompanying three sheets of drawings in

Figure 1 is a side elevation of a drilling machine or parts with my improved belt driving gearing applied thereto. Fig. 2 is a rear elevation on an enlarged scale of the power shaft and driving shaft. Fig. 3 is a side elevation of the parts shown in Fig. 2. Fig. 4 is a side elevation on an enlarged scale of the top of the machine. Fig. 5 is a partial view, similar to Fig. 4, showing the parts in a different position. Fig. 6 is a plan of the parts shown in Fig. 4, and Fig. 7 is a diagrammatic view illustrating the operation.

Referring to the drawings and in detail, A designates the frame of the drill press, which frame has the usual table or support adjustably mounted thereon. A head or carrier B is adjustably mounted on the frame of the machine and mounted axially adjustable therein is a quill C in which is journaled the drill spindle D, which, in the particular machine, forms the driven shaft to which power is to be applied. A carrier E is adjustably mounted at the top of the frame. Journaled on top of this carrier is a pulley F. This pulley, in the particular apparatus shown, is made in the form of a two-step pulley. This pulley F is arranged to drive the drill spindle D in any approved way, the drill spindle being vertically adjustable through the pulley F for the purpose of the feed.

The parts previously described may be of any ordinary or approved construction.

The carrier E may be adjusted vertically to either one of two positions, as shown

in Figs. 4 and 5, by means of a pivoted bell-crank lever 10 and link 11 so as to bring either step of the pulley F into operative position.

Extending rearwardly from the frame is a supporting arm or bracket 12, fitted to slide horizontally on which is a plate 13. Mounted in brackets carried by the plate 13 is a shaft on which a quarter turn idler pulley G runs. Pivoted to the plate 13 is a bracket 14 which carries a shaft on which an idler H runs. Extending from this bracket 14 is an arm which has a pin 15 engaging a slot in a cam 16. This cam has slots at its ends through which pass screws 17-17 threaded into the frame, these parts being so arranged that the cam can slide back and forth on the plate 13. A bell-crank lever 18 is pivoted in the frame of the machine and has one end connected to the adjustable carrier E and the other end to said cam 16 by a link 19. The plate 13 can be adjusted back and forth on the bracket 12 by means of a screw 20 which is threaded into a nut 21 depending from the plate, and which screw can be operated by means of bevel gears 22-22 and a hand wheel 23. The general purpose of this construction is to keep the idler H automatically in proper position to deliver the quarter turn belt, hereinafter referred to, properly to the pulley F, and to either step thereof, depending upon the vertical adjustment of the carrier E; and also to keep the return idler in proper position as the plate 13 is adjusted horizontally by the hand wheel 23 to put the quarter turn belt under the right tension for the work being done. The general details of this mechanism are shown, described and claimed in my Patent No. 962,690, dated June 28, 1910.

I designates the power shaft to which power may be applied by means of loose and tight pulleys 24 and 25. This shaft I may extend along horizontally so that the same shaft can be used to impart power to a number of vertically driven shafts or drill spindles. Mounted on the power shaft I is a pulley J which preferably is made in the form of a step cone, three steps being shown in the construction illustrated.

K designates a driving shaft. This shaft is journaled in arms 26-26. These arms are pivoted on a shaft 27 which is fixed in the framing, a stop 28 limiting the downward motion of the driving shaft. Mounted

on the driving shaft K is a pulley L, and a quarter turn belt M extends from said pulley L on the driving shaft around said idlers to the pulley F on the driven shaft. A second pulley N is mounted on the movable driving shaft K and this pulley is preferably made to have three steps so that a belt can be used to take the power from the pulley J on the power shaft I to this pulley N, and so that the belt can be adjusted to obtain different speeds between these two pulleys. By this arrangement, six different speeds can be obtained; that is to say, by adjusting the quarter turn belt M to run to either step of the driven pulley F, two different speeds can be obtained, and by adjusting the belt O to different positions on step pulleys J and N, three different speeds can be obtained and the total number of speeds possible is the product of these two numbers, or six different speeds. By properly designing the pulleys, a progressive series of speeds can be obtained, which is desirable for operating machines of the class referred to, so that proper speeds may be obtained for any class of work.

When an adjustment is to be made, the hand wheel 23 is moved so as to adjust the quarter turn idlers G and H to relieve the tension on the quarter turn belt M. This at the same time will relieve the tension on the belt O. Usually, in making a new belt adjustment, the quarter turn idlers G and H are moved far enough toward the spindle to allow the driving shaft K to swing downwardly until the pivoted arms 26 engage the stop 28. This engagement will hold the driving shaft K in position where the belt M can be adjusted to either step of the driven pulley F without any drag from the weight of said driving shaft K and the parts supporting the same and mounted thereon. It also will be noted that when the driving shaft is in this lowered supported position, the tension on the belt O will be relieved so that a new belt adjustment can be easily made between the power shaft I and the driving shaft K. The new adjustment desired can be made by moving the carrier E up or down to bring either step of the driven pulley F into position, or the belt O may be adjusted to a different position on the pulleys J and N, or both adjustments can be made. Then when the desired belt adjustment is obtained, the hand wheel 23 is turned so as to move the plate 13 to the rear, which moves the quarter turn idlers to put the quarter turn belt under tension. The quarter turn belt being put under tension will pull up on the pulley N and thus will pull up on the movable driving shaft K, which action will put the other belt O under tension. It will be noticed that the center of movement of the driving shaft K is the center of the shaft 27 and that as the

belts are put under tension, the driving shaft K will be constrained to swing on an arc struck about the center of the shaft 27, as illustrated in Fig. 7. This will give a toggling or increased leverage movement between the power shaft I and the driving shaft K. In other words, the toggling effect will be obtained by the movement of the driving shaft K on the arc *a* struck around the center 27, as opposed to the normal swinging movement of said shaft K on an arc *b* struck around the center of the shaft I. The result of this construction is that the lower or first belt O will be put under a heavier tension than the quarter turn belt M. This is a very desirable feature, particularly when the belt O is running from the small step on the pulley J to the large step on the pulley N, because the tension of the belt O can be so increased, relatively to the tension of the belt M, that the belt O will not slip. This adjustment is usually made when the spindle is driving a large drill or tool requiring a slower speed and a great deal of power. This increased tension on the belt O overcomes the effect of the decrease in the surface wrap due to the difference in the size of the pulleys and to the shortness of the belt. The same advantages are obtained when the belt is on the small step of the pulley J. When an adjustment is to be made, all that is necessary is to manipulate the hand wheel 23 to adjust the idlers to relieve the tension of both belts, to make the proper adjustment, and then to adjust the hand wheel 23 to move the idlers rearwardly, which will put both belts under tension and which will put the lower belt under a greater tension than the upper belt, which will give a proper belt drive, even if the machine is required to do heavy work. Thus, a gearing is provided which is particularly advantageous for use in the locations specified.

The details and arrangements herein shown and described may be greatly modified by a skilled mechanic without departing from the scope of my invention as expressed in the claim.

Having thus fully described my invention, what I claim and desire to secure by Letters-Patent is:—

In a machine tool, in combination a frame, a power shaft mounted horizontally in said frame, a driven shaft mounted vertically in said frame, an intermediate shaft movably supported in horizontal position above and to the rear of said power shaft by a pair of swinging arms pivoted to said frame at points located substantially in the vertical plane of said power shaft and substantially in the horizontal plane of said intermediate shaft, a pulley on said power shaft, a pulley on said intermediate shaft, a short belt running over said pulleys and thereby driving

5 said intermediate shaft from said power shaft, a driving pulley on said intermediate shaft, a pulley on said vertical shaft, a pair of idler pulleys mounted substantially vertically above said intermediate shaft and substantially in the plane of the pulley upon the vertical shaft in position to guide a belt running from the driving pulley upon the intermediate shaft to the pulley upon the 10 vertical shaft, a quarter-turn belt passing substantially vertically from the driving pulley on said intermediate shaft to the idler pulleys and from said idler pulleys to the pulley on said vertical shaft, and means to

tighten said quarter-turn belt, the angular 15 position of said idler pulleys, said intermediate shaft and said power shaft being such that tightening of the quarter-turn belt is also effective to tighten the short belt in greater degree. 20

In testimony whereof I have hereunto set my hand, in the presence of two subscribing witnesses.

HARDING ALLEN.
